F. HALLER

ILLUMINATED WRITING IMPLEMENT

Original Filed May 23, 1923

FIG. 1

FIG. 2

FIG. 3

INVENTOR
F. Haller

BY *Marvin Palmer*
ATTORNEY

UNITED STATES PATENT OFFICE.

FRITZ HALLER, OF NEW YORK, N. Y.

ILLUMINATED WRITING IMPLEMENT.

Application filed May 23, 1923, Serial No. 640,853. Renewed August 7, 1926.

This invention relates to improvements in writing instruments and has for its object to provide an instrument carrying illuminating means.

5 Another object of the invention resides in the provision of a source of energy arranged to be concealed within the instrument and which may be readily renewable.

A further object of the device is to provide a pen having its cap so arranged that when removed from its position inclosing the point, placed upon the opposite end and screwed into position, contact will be made so as to complete an electrical circuit through

15 the illuminating element.

With these and other objects in view, which will become more apparent as the description proceeds, the invention consists in the novel construction, combination and arrangement of parts which will be fully set forth in the following specification, and illustrated in the drawings in which:—

Figure 1 is a side view of a pen showing the cap in writing position and partly in section.

Figure 2 is a view similar to Figure 1 showing the cap enclosing the point.

Figure 3 is a longitudinal sectional view through Figure 1.

30 Referring to the drawing in detail, the numeral 10 designates the barrel of the pen, which is tapered near one end as at 11. Formed intermediate the ends of the tapered portion 11 are screw-threads 12 for cooperation with the internal threads of the cap, which will be more fully hereinafter described. Similar threads 13 are formed near the opposite end of the barrel as clearly shown in the drawing.

40 The tapered end of the barrel 10 carries the customary nib 14 and feeder 15 which is connected to the open end of the ink sack 16 normally contained within the barrel.

45 As shown in Figure 3, the end wall 17 of the barrel 10 is provided with a central opening for the reception of an insulating bushing 18 which is pierced to receive a conductor 19.

50 As shown, the inner end of the conductor 19 bears against and is secured in electrical

contact with a metallic strip 20, supported in spaced relation to the barrel 10 on a suitable strip of insulating material 21.

The barrel 10 is provided near the writing end with a threaded opening 22 for the reception of the base of an incandescent lamp bulb 23, the central contact of which bears against the free end of the metallic strip 20.

55 The cap, designated generally by the numeral 24, comprises a cylindrical body 25 closed at one end as at 26, and provided at the opposite end with internal screw-threads 27.

60 Secured to the end closure 26 of the cap, 65 is a spring contact element 28 for engagement with one pole of an electric cell 29, contained within the cap 24 and the opposite pole 30 of said cell is adapted to bear on the outer free end of the conductor 19.

70 In use, the cap is removed from the tapered end 11 in the customary manner and placed on the opposite end of the barrel 10 as clearly shown in Figures 1 and 3, and upon turning the cap so as to cause the threads to draw the same onto the barrel, it will be seen that the pole 30 will be firmly and yieldably engaged with the conductor 19.

75 At the same time, the contact element 28 will complete contact with the opposite pole of the cell 29, so that a circuit will be completed through the lamp 23. Obviously upon removing the cap and replacing the 80 same on the tapered end 11 of the barrel 10, the circuit will be broken and loss of energy prevented.

85 Having thus described my invention and set forth the manner of its application and use, what I claim as new and desire to secure by Letters Patent, is:—

90 The combination with a writing implement having a tubular body provided with screw threads adjacent each end thereof and a cap engageable over either end by said threads, said cap containing a chamber beyond the part occupied by the body in either position, a battery cell in said chamber in electrical engagement therewith, a lamp bulb removably engaged directly in the wall 95 100

of said body, and in electrical engagement therewith, said bulb being located between the screw threads adjacent the operative end of the implement, the stem of the lamp extending through the body wall into the interior thereof, a spring arm fixed at one end in said body and insulated therefrom, the

opposite end of said arm being in electrical engagement with the central contact of the lamp, and an electrical connection between 10 the battery cell and fixed end of said arm.

In witness whereof I have affixed my signature.

FRITZ HALLER.
